[57] ABSTRACT

Process for the thermal destruction of hazardous organic wastes utilizing high temperatures (2200° F.-3000° F.), long retention times (1.5-4 seconds), and high pressures (300+psi) in a reactor having a controlled partial oxidation environment to thermally break the bonds of organic molecules into CO, CO₂, H₂, and acid gases (such as H₂S, HCN, HCl). In the preferred embodiment, pulverized coal, organic waste matter, and slurry water are pumped into the reactor vessel. The

coal and waste matter are both broken into simple gases and the slurry water is split into hydrogen and oxygen. Downstream processing equipment removes particulates, acid gases, and CO₂ making a product gas suitable for use as a fuel or chemical feedstock.

The process has distinct advantages over existing thermal hazardous waste destruction processes including, but not limited to, (1) energy and materials conservative, (2) fewer process control parameters, (3) can operate independent of waste availability, (4) limited exposure to the environment of any byproducts, (5) ability to recycle any incomplete destruction products, (6) most metals entering the system are fixated in a silicate slag, and (7) can handle waste not suitable to conventional incineration. This timely invention can help solve both the energy problem and problems with hazardous waste disposal.
